(57) **CLAIM**

The ornamental design for protective cover, as shown and described.

DESCRIPTION

FIG. 1 is a perspective view of a protective cover showing our new design in an open configuration;

FIG. 2 is a second perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and

FIG. 8 is a right side elevation view thereof.

FIG. 9 is a perspective view of the protective cover showing our new design in a closed configuration;

FIG. 10 is a second perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof; and

FIG. 16 is a right side elevation view thereof.

FIG. 17 is a perspective view of the protective cover showing our new design in an upright configuration;

FIG. 18 is a bottom plan view thereof;

FIG. 19 is a rear elevation view thereof;

FIG. 20 is a left side elevation view thereof; and,

FIG. 21 is a right side elevation view thereof.

Broken lines shown in the drawings show unclaimed subject

matter and form no part of the claimed design.

1 Claim, 11 Drawing Sheets
